UNITED STATES PATENT OFFICE.

CHARLES D. BROUYETTE, OF TOPEKA, KANSAS.

BED BOTTOM.

Application filed September 9, 1921. Serial No. 499,470.

To all whom it may concern:

Be it known that I, CHARLES D. BROUYETTE, a citizen of the United States, residing at Topeka, in the county of Shawnee and

5 State of Kansas, have invented certain new and useful Improvements in Bed Bottoms, of which the following is a specification.

My invention relates to a bed bottom of the type comprising helical springs which

10 are held in proper position by a wire fabric or structure articulated with the upper coils of the springs. The principal object of my invention, generally speaking, is to provide a novel bed bottom of this type which 15 will be strong, durable, very flexible and resilient, and inexpensive to manufacture.

More particularly, the invention contemplates making the wire fabric or structure of a plurality of elements of identical form

20 (except as modification is necessary at the margins of the structure), which elements are interengaged with the springs, and preferably also with each other, to provide a fabric for retaining the springs in their 25 proper upright position, which will be flexible, both longitudinally and transversely of the bed bottom without involving any bending of the wires of which said fabric is made. That is to say, there are no wires, at least

30 there need be no wires, which extend across the structure from side to side, or from end to end, the fabric being made up essentially of short links articulated with the springs and with each other in such a manner that

35 the desirable flexibility in both directions is provided for by the articulations themselves. As a result of this arrangement, the bed bottom is more resilient, and at the same time more durable, than one involving wires 40 or cross rods which extend continuously across the structure, and must therefore bend on depression of any part of the bed bottom.

The invention which is illustrated in the 45 accompanying drawings in several forms consists of the novel and improved arrangements and devices for carrying out the above stated objects, and such other objects as will be mentioned in the following description of 50 the illustrated structures.

In the drawings:

Fig. 1 is a fragmentary plan view of a bed bottom constructed in accordance with my invention;

55 Fig. 2 is a vertical sectional view on line 2-2 of Fig. 1;

Fig. 3 is a view in perspective of one of the articulations constituting a characteristic feature of the invention;

Fig. 4 is a fragmentary view in perspective of one of the links for holding the 60 springs in their proper positions;

Fig. 5 is a fragmentary plan view illustrating a modification;

Fig. 6 is a view in perspective of the type 65 of articulation employed in the construction shown in Fig. 5; and

Figs. 7 and 8 are figures corresponding to Figs. 5 and 6, respectively, illustrating another modification.

Referring first to Figs. 1, 2, 3 and 4: the bed bottom therein shown is composed of a plurality of helical springs 10 of any suitable form, and a plurality of links 11 (Fig. 4) engaged with each other and with the 75 upper coils of the springs in the peculiar manner shown. The bed bottom will necessarily be supported upon a suitable supporting framework which may be of any desired construction. I have indicated an 80 angle iron framework 12 having supporting wires 13 attached thereto, springs 10 being mounted upon and attached to the supporting wires, as indicated at 14 (Fig. 2). The upper coils of the springs are attached 85 by binding wires 15 to a rectangular frame 16, preferably made of heavy wire. The mounting and attachment of the springs upon and to the supporting structure are matters of common practice, and form no 90 part of my invention.

The springs are preferably arranged in parallel rows, this being the common practice, and the connecting links 11 are disposed in a plurality of series between the 95 several rows, the series of links being in parallel and the links of each series arranged end to end. Each link engages the ends of adjacent links and four of the springs. The construction therefore does away entirely 100 with any wires or other fastening means extending transversely of the links. This arrangement simplifies the structure in comparison with bed bottoms as heretofore made, and reduces the cost of manufacture, 105 besides giving flexibility in both directions, as will be seen by consideration of the nature of the articulations provided for.

The upper coils 17 of the springs are formed with bends adapted to be engaged 110 by the links. In the construction shown in Figs. 1, 2, 3 and 4, these bends or offsets 18

are made by bending the wire of the coil at two points only; viz, at 19 and 20. This method of producing the offset is desirable when the wire of the spring is stiff and brittle, so that a minimum of bending is advisable.

In the construction shown in Figs. 5 and 6, the bend 21 is in the form of an indentation made by bending the wire at three points; 10 viz, 22, 23 and 24. In the construction shown in Figs. 7 and 8, the wire of the spring is also bent at three points; viz, 25, 26 and 27, but so as to produce an outward projection 28. The construction shown in Figs. 5 to 8 15 inclusive has certain advantages, as will be hereinafter mentioned, but involves a disadvantage if the wire of the springs is liable to breakage when bent to the extent necessitated in these arrangements.

20 Returning to the construction shown in Figs. 1 to 4 inclusive, the link 11 consists, preferably, of a single piece of wire bent to a three-sided configuration, providing two substantially parallel members 29 joined at 25 one end of the link by a cross member 30, the extremities of the wire being each bent first backwardly to form a loop 31, and then forwardly to form a loop or hook 32. The cross member 30 is preferably offset a trifle below 30 the plane of members 29.

The link thus formed is placed so that the cross member 30 bears against the edges of the bends 18 of oppositely arranged springs, the members 29 extending across the tops 35 of the offsets. The loops 31 extend over and around the offsets of the next pair of springs (to the left of Fig. 1), and the loops or hooks 32 extend over, around and under the cross member 30 of the adjacent link. The 40 links are thus articulated flexibly end to end, and the series of links are articulated flexibly with the springs in such a way as not to slip on the springs, thereby holding the springs in proper relation, one with another, 45 but so as to allow the tops of the springs to cant, if necessary. That is to say, the links will turn one upon the other on axes at right angles to the axes of the turning movements as between the links and the springs.

50 The differences between the constructions shown in Figs. 5 to 8 inclusive, and the construction shown in Figs. 1 to 4 inclusive, with respect to the form of the bends or offsets in the springs, have already been noted. The 55 constructions of Figs. 5 to 8 inclusive have, however, this advantage, that they permit a reverse arrangement of the links of alternate series. This arrangement is not essential, as the links might be turned all in the same 60 direction, as in Figs. 1 to 4, but when they are reversed in alternate series, as shown in Figs. 5 to 8, the possibility of the tops of the springs tilting laterally, so to speak, which is present in the first described construction, is obviated. That is, referring to

Fig. 1, the right-hand side of the spring cannot tilt downwardly because members 29 of the links extend across the projections 18, but the left-hand sides of the spring may tilt down to a certain extent. If it is 70 deemed desirable to correct this, the bends in the springs may be formed as shown in Figs. 5 and 6 or Figs. 7 and 8, and the links in alternate series reversed. Take for example the spring shown in the lower part of Fig. 5: the member 29^a of link 11^a extends over the projection 23 at one side of the spring, while the oppositely turned link 11^a on the other side of the spring extends across the projection 23 in the opposite direction. 80 This prevents tilting of the spring either way.

A similar result is obtained by the arrangement shown in Figs. 7 and 8. In Figs. 7 and 8 the links 11^b of alternate series are 85 also turned in opposite directions. The articulations of the modified constructions are in other respects the same as those described in connection with Figs. 1 to 4 and in the drawings the parts are given corresponding 90 numerals with the exponents "a" and "b" respectively.

In all the constructions shown, the end links of the series will have their extremities looped around the retaining wire or frame 95 16, as shown at 33.

While I have described my invention in certain preferred embodiments, it will be understood that further modifications are possible within the scope of the invention as 100 defined by the claims appended hereto.

I claim:

1. In a bed bottom, the combination of helical springs formed with lateral bends, and links consisting each of a wire formed 105 to provide a pair of members joined by a cross member, the links being arranged in series, end to end, between the springs, and the extremities of each link being formed with pairs of oppositely disposed loops extending lengthwise of the link, one below the other, in each case, the upper pair of loops engaging the bends of adjacent springs and the lower loops the cross piece of another link. 110

2. In a bed bottom, the combination of helical springs formed with lateral bends, and links consisting each of a wire formed to provide a pair of members joined by a cross member offset downwardly from the 115 other members, the links being arranged in series, end to end, between the springs, and the extremities of each link being formed with pairs of oppositely disposed loops extending lengthwise of the links; and one below the other, in each case, the upper pair of loops engaging the bends of the adjacent springs and the lower loops the cross piece of another link. 120

3. In a bed bottom, the combination of 125

helical springs formed with lateral bends, and links consisting each of a wire formed to provide a pair of members joined by a cross member offset downwardly, the links being arranged in series, end to end, between the springs, and the extremities of each link being formed to engage the lateral bends of adjacent springs and also the cross member of another link.

5. 4. In a bed bottom, the combination of helical springs arranged in rows, and means for retaining the springs in position comprising a series of three-sided wire links between each two rows of springs, the links being articulated with each other and with said springs, and the links in each series being turned in the opposite direction from that of the links in the adjacent series.
- 10 5. In a bed bottom, the combination of helical springs arranged in rows, each of the springs being provided with a triple

bend at each side, and three-sided wire links arranged end to end and articulated with each other and with said springs for holding the springs flexibly in position, said links being arranged in alternate rows in opposite directions. 25

6. In a bed bottom, the combination of helical springs arranged in rows, each spring being formed with a pair of oppositely disposed inwardly extending projections, and a plurality of links consisting each of a wire formed to provide a pair of members joined by a cross member, the links being arranged in series, end to end, between the springs, with the links of alternating series turned in opposite directions, and the extremities of the links being formed to engage the projections of an adjacent pair of springs, and also the cross member of another link. 30 35

CHARLES D. BROUYETTE.
